APPARATUS FOR IMPRESSING TYPE FACE
Anton N. Lewandoski, 1706 St. Clair River Drive,
Algonac, Mich.
Filed July 26, 1962, Ser. No. 212,578
5 Claims. (Cl. 101—6)

This invention relates to a novel and useful apparatus for impressing type face.

In the printing industry there has been in recent years a greater call for type of printed material which includes portions that are very distinctive and stand out from the rest of the printed material. The advertising industry is the main user of printed material of this type and the appearance and appeal of an ad can be greatly improved by the use of portions of the printed ad which stand out from the remainder thereof.

While different portions of an ad may be printed with different size or design of type face, the general public is accustomed to seeing these older methods of attracting attention to ads and accordingly there has been a relatively recent move toward using boldfaced type having a design incorporated therein.

Heretofore printed material having boldfaced letters therein on which a design is formed was produced by first printing the ad with conventional boldfaced type and then making a photograph of the printed material with a grid or mat having a given design disposed over certain portions of the material which was to have a design formed thereon. Then, the photograph, having the designed boldfaced type thereon, could be reproduced on an engraving plate in order that the desired ad could be printed including broad faced lettered portions thereof having designs thereon. This method of reproducing broad faced printing material having a design thereon is of course very time consuming and costly. In addition, such methods may not be practiced in other than large metropolitan areas where photoengraving facilities are available.

It is accordingly the main object of this invention to provide an apparatus for impressing the broad faced type slugs themselves which are to be used in printing advertising and other literature which is to include broad faced type having a design formed thereon.

A further object of this invention, in accordance with the immediately preceding object, is to provide an apparatus which will be capable of simultaneously forming a plurality of separate designs on the transfer face of a plurality of type slugs.

Yet another object of this invention, in accordance with the immediately preceding objects, is to provide an apparatus which will conform to conventional forms of manufacture, be of simple construction and easy to use so as to provide a device that will be economically feasible, long lasting and relatively trouble free in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the apparatus of the instant invention;

FIGURE 2 is an end elevational view of the apparatus as seen from the left side of FIGURE 1;

FIGURE 3 is a longitudinal vertical sectional view taken substantially upon the plane indicated by the section line 3—3 of FIGURE 2;

FIGURE 4 is a longitudinal vertical sectional view taken substantially upon the plane indicated by the section line 4—4 of FIGURE 2;

FIGURE 5 is a transverse vertical sectional view taken

2

substantially upon the plane indicated by the section line 5—5 of FIGURE 1; and

FIGURE 6 is a fragmentary plan view of the transfer face of a broad faced type slug whose transfer face has been impressed by the apparatus of the instant invention in order to have a design formed thereon.

Referring now more specifically to the drawings the numeral 10 generally designates the apparatus of the instant invention which includes a base generally referred to by the reference numeral 12 that is adapted to be secured to a supporting surface such as the top of the table 14 in any convenient manner.

A bed plate generally referred to by the reference numeral 16 is secured to the base 12 in any convenient manner and has a plurality of upwardly opening slots 18 formed therein which extend longitudinally of the bed plate 16 and open through the opposite ends thereof. In addition, the sides 20 of the bed plate 16 have a pair of oppositely opening slots or grooves 22 formed therein.

A pair of buttresses 24 are removably secured to each end of the base 12 by means of fasteners 26 and an abutment plate 28 is removably secured between each pair of buttresses 24 and the corresponding end of the bed plate 16.

An embossing roller carriage generally referred to by the reference numeral 30 is provided and is generally U-shaped in configuration including a pair of depending legs 32 interconnected at their upper ends by means of a bight portion 33. Each of the legs 32 is provided with an inverted flange 34 on its lower end which is snugly and slidably received in the corresponding slots 22. In this manner, the roller carriage 30 is guidingly supported from the bed plate 16 for reciprocal movement longitudinally of the bed plate 16. The legs 32 each have a slot 36 formed therein and the opposite ends of a support shaft 38 project through and are rotatably and slidably received in the slots 36. Each end of the support shaft 38 which projects outwardly of the roller carriage 30 has a gear wheel 40 mounted thereon and a pair of rack gears 42 are secured to the base 12 in any convenient manner such as by means of fasteners 44. The gear wheels 40 are aligned and meshed with the rack gears 42 and a crank handle 46 is fixedly secured to one end of the support shaft 38.

A pair of journal blocks 48 each include a shank portion 50 which is slidably received through a corresponding slot 52 formed in the bight portion 33 and the shank portion 50 of each journal block 48 is secured to an apertured mounting plate 54 by means of a suitable fastener 56. The mounting plates 54 are each supported from the bight portion 33 by means of a plurality of standard studs 58 having adjusting nuts 60 threadedly engaged therewith and compressively engaging portions of the mounting plates 54 therebetween. In addition, a pair of abutment studs 62 are threadedly engaged through complementary threaded bores 64 formed in the bight portion 33 and held in adjusted position by means of jam nuts 66. A journal block 68 is rotatably supported from the lower end of each of the abutment studs 62 and rotatably journals the shaft 38. It is to be understood that the journal blocks 48 each also rotatably journal the shaft 38.

Disposed between adjacent ones of the journal blocks 48 and 68 are a plurality of embossing rollers 70 which each has an individual design formed in its outer surface. The embossing rollers 70 may of course be raised and lowered relative to the upper surface 72 of the bed plate 16 upon the raising and lowering of the shaft 38.

It is to be understood that the shaft 38 will be adjusted only slightly relatively to the bed plate 16 and therefore that the gear wheels 40 will remain in proper meshed engagement with the rack gears 42. However, if it is desired to appreciably change the height of the shaft 38 above the bed plate 16, either a larger diameter gear wheel

40 may be provided or the rack gears 42 may be shimmed up in order to be properly positioned relative to the raised gear wheels 40.

With attention now directed to FIGURES 1 and 4 of the drawings it will be seen a second roller carriage generally referred to by the reference numeral 74 which is substantially identical to the roller carriage 30 with the exception that it is provided with journal blocks 76 similar to journal blocks 68 that are each supported from abutment studs 78 similar to abutment studs 62.

The embossing rollers 80 carried by the shaft 81 of the roller carriage 74 may each have a different design formed thereon and a design which is different from the designs formed on the embossing rollers 70.

With attention now directed to FIGURE 5 of the drawings it may be seen that a plurality of type slugs 82 are received within the slots or grooves 18 and that the laterally enlarged heads 84 of the type slugs 82 abut the upper surface of the bed plate 16. Each of the type slugs 82 includes a transfer face 86 which may be formed in the shape of a plurality of letters such as those illustrated in FIGURE 6 of the drawings and by rolling certain of the embossing rollers 70 and 80 across the transfer faces 86, the design of the rollers 70 and 80 may be transferred to or impressed in the transfer faces 86 of the type slugs 82.

With attention now directed to FIGURE 1 of the drawings it may be seen that the roller carriage 30 is provided with a plurality of upstanding pins 90 and that the roller carriage 74 is provided with a similar pair of pins 92. A pair of connecting straps 94 are apertured at opposite ends to receive the corresponding pairs of pins 90 and 92 whereby the straps 94 are secured between the roller carriages 30 and 74 in order that the roller carriage 74 may be reciprocated simultaneously and equally with roller carriage 30.

In this manner, type slugs to be embossed by the rollers 80 may be placed in the ends of the grooves 18 at the left side of FIGURE 1. The type slugs to be impressed by the rollers 70 are then placed in the other ends of the slots or grooves 18. During movement of the carriages 30 and 74 to the left, the embossing rollers 80 will impress the type slugs disposed in the adjacent ends of the slots 18. Then the carriages 30 and 74 may be moved toward the far end of the bed plate 16 whereupon the distant type slugs will be embossed by the embossing rollers 70. Prior to the return of the carriages 30 and 74 to the adjacent end of the bed plate 16, the type slugs 82 embossed by the rollers 80 may be removed and substituted for by new slugs which are to be embossed.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. An apparatus for impressing the transverse base of type slugs with a predetermined design, said apparatus comprising an elongated base adapted to be secured to a supporting surface, said base including a bed plate extending longitudinally thereof and having a plurality of

upwardly opening and longitudinally extending slots formed therein adapted to receive an elongated type slug with the transfer face thereof disposed uppermost and above the portions of the bed plate defining the upper extremities of said slots, said bed plate including a pair of longitudinally extending opposite sides and means defining a pair of longitudinal slots therein opening outwardly away from said bed plate, said sides, above said slots, being parallel and planar, a generally inverted U-shaped carriage including a pair of depending plate-like legs interconnected at their upper ends by means of a plate-like bight portion extending transversely of said bed plate and disposed a spaced distance above the first-mentioned slots, the lower ends of said legs including inwardly directed flanges snugly and slidably received in the opposite side slots, the lower ends of said legs, immediately adjacent said flanges, slidably engaging said sides above said opposite side slots, each of said legs defining an upstanding slot disposed above the corresponding flange, a support shaft, the opposite ends of said support shaft being snugly, slidably and rotatably received in the last-mentioned slots, a plurality of embossing rollers journaled on said shaft and spaced longitudinally of the latter in registry with certain of the first-mentioned slots, individual journal means on said shaft between each pair of adjacent rollers and disposed between said bed plate and said bight portion, means mounting each of said journal means from said bight portion for individual positive adjustment toward said bed plate, journal means on said shaft between each of said legs and the adjacent roller, and individual adjustment means connected between said bight portion and said last-mentioned journal means operable to adjustably vary the maximum spacing between said bed plate and said last-mentioned journal means.

2. The combination of claim 1 including means connected between said carriage and said base for effecting reciprocation of said carriage longitudinally of said bed plate.

3. The combination of claim 1 including a rack gear carried by said base and extending longitudinally thereof and in a direction paralleling the movement of said carriage, said last mentioned means comprising a gear wheel mounted on said support shaft for rotation therewith and meshed with said rack gear, a crank handle mounted on said shaft for effecting its rotation.

4. The combination of claim 1 including an abutment plate removably secured across the open ends of one set of corresponding ends of the first mentioned slots.

5. The combination of claim 1 including a second carriage guidably mounted on said bed plate for guided rectilinear movement longitudinally thereof and including at least one embossing roller journaled for rotation about an axis extending transversely of said bed plate and adjustable toward and away from said bed plate, means rigidly and removably interconnecting said carriages for simultaneous and equal reciprocation.
